Primary Examiner — Messina L Smith*Assistant Examiner* — Aram Kwon(57) **CLAIM**

The ornamental design for a digital audio player, as shown and described.

DESCRIPTION

1. Digital audio player

1.1 : Perspective

1.2 : Perspective

1.3 : Front

1.4 : Back

1.5 : Left

1.6 : Right

1.7 : Top

1.8 : Bottom

The figures illustrate the digital audio player which reproduces high-quality music files.

1 Claim, 8 Drawing Sheets(56)
